WRITING INSTRUMENT

Donald Duane Furman, Beloit, Wis., assignor to The Parker Pen Company, Janesville, Wis., a corporation of Wisconsin

Application December 15, 1958, Serial No. 53,773

Term of patent 14 years

(Cl. D74—17)

Fig. 1 is an elevational view, from any side, of a writing instrument embodying my new design;

Fig. 2 is an enlarged top plan view thereof as seen from line 2—2 in Fig. 1; and

Fig. 3 is an enlarged bottom plan view thereof as seen from line 3—3 in Fig. 1.

I claim:

The ornamental design for a writing instrument, as shown.
